No. 734,205.

PATENTED JULY 21, 1903.

G. E. WALTER.
FIRE RESISTING DOOR.
APPLICATION FILED MAR. 3, 1903.

NO MODEL.

UNITED STATES PATENT OFFICE.

GUSTAVE E. WALTER, OF NEW YORK, N. Y., ASSIGNOR TO THE ASBESTOLITH COMPANY, A CORPORATION OF NEW JERSEY.

FIRE-RESISTING DOOR.

SPECIFICATION forming part of Letters Patent No. 734,205, dated July 21, 1903.

Application filed March 3, 1903. Serial No. 145,925. (No model.)

To all whom it may concern:

Be it known that I, GUSTAVE E. WALTER, residing at New York, in the county of New York and State of New York, have invented 5 certain new and useful Improvements in the Construction of Fire-Resisting Doors, &c., of which the following is a full, clear, and exact description, such as will enable others skilled in the art to which it appertains to make and 10 use the same.

This invention relates to the construction of fireproof or fire-resisting doors and the like; and its object is to provide a simple, durable, and efficient construction of this 15 character.

The invention consists in the features of construction, combinations of elements, and arrangement of parts which will be herein-after fully set forth, and the novel features 20 thereof pointed out in the claims.

In the accompanying drawings, which illustrate an embodiment of the invention, Figure 1 is a side elevation of a door and casing with certain parts of the door broken away 25 to show the construction thereof. Fig. 2 is a section of the door on the line $x-x$ of Fig. 1.

Similar reference characters refer to similar parts throughout both views.

The casing 1 of the door is shown merely for 30 purposes of illustration and forms no part of the present invention. The door proper has a foundation or core which consists of a skeleton frame, preferably of hard wood or other light material, this skeleton frame being 35 made up of vertical side pieces 2 and transverse cross-pieces 3 and 4. Between the side pieces 2 and the cross-pieces 3 and 4 are strips 5, located at intervals around the frame for purposes of stiffening and strength. The 40 upper end only of this skeleton frame is shown; but it will of course be understood that it extends throughout the door. The central panel of the door is formed of netting 6, preferably metallic or galvanized wire-netting, 45 which is connected to the framework by the strips 7, preferably of galvanized sheet metal, the inner ends of which are connected to the netting 6 by means of the bolts 9, and the outer ends of which are secured to the sides 50 of the inner members of the frame, as shown in Fig. 2. The skeleton frame is covered

with strips of asbestos board 10, and the entire door is sheathed with a coating of fire-resisting composition 11, preferably the well-known fire-resisting composition asbestoslith, 55 which is applied in a plastic state and molded to the door by the use of dies, stamps, or otherwise. This outer sheeting may, however, be of any desirable fire-resisting composition which can be readily applied and 60 which would serve the same purpose as the asbestoslith.

It will be seen that the construction described may be easily assembled by fastening the vertical and transverse members of the 65 frame together, inserting the central panel, preferably through the medium of the iron strips, as shown, placing the asbestos board in position on the frame, securing it in any suitable way thereto, if it is desired that it 70 should be fastened to the frame, and molding or pressing the composition thereon. This provides a structure the wooden framework of which is light and sufficiently strong, which has less tendency to warp than if the frame- 75 work were solid, and in which there is an advantage both on the ground of lightness and strength and also because of the fire-resist- 80 ing qualities due to the presence of the air-spaces within the framework and between the stiffening-strips. The body portion of rough asbestos board provides both a stiffening and fire-resisting element and likewise a rough surface, to which the plastic composition can be applied and by which it will be securely held. 85 The presence in the central panel of the wire-netting answers a like purpose of providing a stiffening element which has a surface suitable for the reception of the molded composition. The outer molded composition has the 90 advantage of fire-resisting qualities, strength without the tendency to warp, and since it is applied in plastic form it may be easily made to conform to any desired outline of the door, frame, shutter, partition, or the 95 like, while the edges, where a joint is made with the casing or other adjacent parts, may be sharply defined.

The nature of the composition, which I have termed "asbestoslith," is set forth in the 100 patent to Charles W. Kane, No. 645,033, March 6, 1900, and may be, briefly stated, said to con-

tain calcined magnesite, pulverized dolomite, fibers, silicate of magnesium, muriate of ammonia, chlorid of magnesium, and water. It will be understood, however, that this is merely a preferred form of fire-resisting composition, and it will also be understood that where in the claims I use the word "door" I am not necessarily limited in the use of this invention in connection with a door, as a similar construction might be applied to the trim or framework or to other parts.

Having described my invention, what I claim as new, and desire to secure by Letters Patent, is—

- 15 1. A fire-resisting construction for use in a door or the like, comprising a frame made up of vertical and transverse strips of wood, stiffening-strips located at intervals in said frame between said vertical and transverse strips whereby air-spaces will be left in said frame between said strips, an asbestos-board covering for said frame and a sheathing of a fire-resisting composition incasing said door and molded thereto.
- 20 2. A fire-resisting construction for use in doors and the like, comprising a wooden frame, a central metallic panel, an asbestos-board covering for said frame and an outer incasing sheath of fire-resisting composition.
- 25 3. A fire-resisting construction for use in doors and the like, comprising an inner skeleton frame of wood or other suitable light material, an asbestos-board covering for said

frame, a central panel of metallic netting and an outer sheathing of a fire-resisting composition.

4. A fire-resisting construction for use in a door or the like, comprising a skeleton frame of suitable light material, a central panel of metallic netting fastened thereto, strips of asbestos-board covering said skeleton frame and an outer sheathing of a fire-resisting plastic composition incasing the entire door and molded thereto.

5. A door construction comprising a skeleton wooden frame, a central panel of metallic netting secured to said frame through the interposition of galvanized-metal connecting-strips, an asbestos-board covering for said frame and an outer incasing sheath of a fire-resisting composition applied in a plastic state and molded thereto.

6. In a door construction in combination, a skeleton wooden frame, a central panel of metallic netting secured to said frame, an asbestos-board covering for said frame and an outer inclosing sheath of asbestos, molded to conform to said asbestos covering and said central panel.

In testimony whereof I affix my signature in the presence of two witnesses.

GUSTAVE E. WALTER.
